Aaron Silber, Flushing, and Arthur J. Bellini,
Valley Stream, N. Y.

Application March 29, 1955, Serial No. 35,264

Term of patent 14 years

(Cl. D7—5)

Fig. 1 is a perspective view of a shoe heel showing our new design.

Fig. 2 is a side view of the heel shown in Fig. 1.

Fig. 3 is a rear view of the heel in Fig. 1, and

Fig. 4 is a bottom view of the heel in Fig. 1.

The lined areas on the heel represent inlaid covering material.

We claim:

The ornamental design for a shoe heel, substantially as shown and described.
